HYDRAULIC RAM SYSTEM

Filed April 1, 1929

UNITED STATES PATENT OFFICE

WILLIAM K. MCFARLIN, OF EAST ORANGE, NEW JERSEY

HYDRAULIC RAM SYSTEM

Application filed April 1, 1929. Serial No. 351,591.

This invention relates to improvements in the operation of hydraulic rams and has particular reference to the operation of rams in battery whereby any desired amount of water can be supplied automatically and efficiently.

The main object of the invention is to provide means whereby the length of the drive pipe to each ram of the battery may be established at the desired amount independently of the lengths of the drive pipes to the other rams of the battery and to insure that the water in the drive pipe is always under proper pressure to deliver the desired kinetic kick to the delivery valve of the ram.

A further object of the invention is to provide a water supply system to a battery of rams so that the water will not readily freeze in the pipes and that the water in the supply pipes will always be in motion.

A still further object is to establish the system so that the battery of rams can be placed at any desired distance from the source of the water supply and still operate under the desired head, and whereby the rams can be connected to a city water main, artesian well, flume, or any pipe carrying water under pressure without the need of an extra supply reservoir.

Further and more specific objects, features, and advantages will more clearly appear from the detailed description given below taken in connection with the accompanying drawings which form part of the specification, and which illustrate one embodiment of the invention and in which,

Fig. 1 is a plan view of a battery of rams and their associated apparatus according to my invention, and,

Fig. 2 is a side elevation thereof.

In the present preferred form of the invention as shown in the drawings, the invention is concerned with the assembly and operation of a series or battery of rams such as rams 10-15 suitably disposed in a concrete pit or overflow tank 16, and all connecting to a common delivery pipe 17 leading to any suitable point of delivery for the water to be pumped by the rams. Valves such as 18 are disposed between some of the

rams and the delivery pipe 17. A valve such as 19 is disposed beyond the last ram 15 in the delivery pipe 17.

The battery of rams are supplied through several drive pipes 20-25 which connect to the rams in the usual manner, since the rams are of any standard type. Valves such as 26 are disposed between most of the rams and the drive pipes and are operated through hand wheels. A valve 27 disposed in the drive pipe leading to the first ram 10 is of the quick-throw type operated by a lever 28 so that this ram may be opened very quickly when desired. At the opposite ends of the drive pipes 20-25 are disposed a plurality of devices termed impulser 30-35. These preferably comprise iron tanks generally about three feet high and provided with connections to join the tanks to the drive pipes on one side and to the series of control pipes 36-41 on the other side. In the control pipes 36-41 are disposed valves such as 42 whereby the amount of flow to the impulser tanks can be regulated.

At their opposite ends each of the control pipes are connected to a common distributing tank 43 which has a capacity large enough to distribute water to each ram at initial head pressure. On the opposite side of the distributing tank 43 there is connected a supply pipe 44 which may be unlimited as to length but must have capacity sufficient to maintain a full head pressure on the distributor tank 43 when all the rams are working.

Operation

The supply pipe 44 extends from a suitable source of water supply such as a river, a well, a water main, etc., and must be of such dimension that it will at any time be able to carry enough water to supply all the rams when working full capacity. This supply then runs into the distributor where it divides up into the control pipes 36-41 which may be of variable length and never larger than the drive pipes 20-25 but may be smaller depending upon the pressure head used in the distributor tank 43. Their capacity is always in excess of the amount each ram at full capacity will use, and the flow in the

control pipes never entirely ceases consequently the water in them is not liable to freeze. The gate valves 42 are used to complete the control of the water flowing to each ram and when necessary to limit the pressure head in the various impulser tanks 30-35.

The impulser tanks above mentioned are used to allow water to continue to flow in the control pipes even though it may be stopped in the drive pipes. This builds up an air pressure in the impulser tanks which quickens the water flow in the drive pipes for the next stroke. The working head or pressure that can be used in the impulser tanks is about 50% of the head to which the water is to be delivered, being the limit at which the rams will work.

The drive pipes 20-25 are of the diameter called for by the size of the rams to be used but vary in length depending upon the ratio. The water flowing in these pipes stops entirely with each stroke of each ram.

The gate valves 26 and 27 are used for starting and stopping the rams and are always full open when the rams are running. At least one valve such as 27 should be of the quick opening type to fill the delivery pipe high enough to allow the rams to work automatically.

The water flowing in through the supply pipe 43 will be distributed into the various control pipes in accordance with the degree to which the gate valves near the impulser are opened. The presence of these impulser, which are in effect elastic cushions for the water, permits the water to flow continuously in the control pipes and therefore avoid starting and stopping such a large amount of water as would otherwise be the case. The water in the drive pipes however will be started and stopped as usual and will be given a quicker impulse to start them than usual because of the presence of the impulser compressed air pressure and thus insures quick and effective strokes and recovery of the mechanism. This combination permits wider discretion as to the location of the ram from the supply source and latitude with respect to the length of the control and drive pipes which makes it easier to design and install the system to meet the requirements of any particular job. Also the constant flow being assured, the pipes will not freeze. The parts are few in number and of such construction that no replacement and repairs are necessary over long periods of time. The presence of the impulser cushion prevents also the water hammer which would occur upon every stoppage and back reaction from such large amounts of water as is contained in lengths of drive pipe which might otherwise be required.

While I have described my improvement in detail and with respect to a preferred form thereof, I do not desire to be limited to such

details or form since many changes and modifications may be made and the invention embodied in other forms without departing from the spirit and scope of the invention in its broader aspects. Hence I desire to cover all modifications and forms coming within the language or scope of any one or more of the appended claims.

What I claim as new and desire to secure by Letters Patent, is,

1. A hydraulic ram system comprising a ram, a drive pipe therefor, a control pipe connected to the drive pipe, and an air pressure tank disposed between the control and the drive pipes.

2. A hydraulic ram system comprising a ram, a drive pipe therefor, a control pipe connected to the drive pipe, an air pressure tank disposed between the control and the drive pipes, valve means to regulate the amount of water entering the said tanks, and a distributor tank from which the water enters the control pipe.

In testimony whereof that I claim the invention above set forth, I affix my signature hereto.

WILLIAM K. McFARLIN.
